LLOYD GROFF COPEMAN, OF FLINT, MICHIGAN, ASSIGNOR TO COPEMAN ELECTRIC STOVE COMPANY, OF FLINT, MICHIGAN, A CORPORATION OF MICHIGAN.

TIME-OPERATING MECHANISM FOR ELECTRIC SWITCHES.

1,104,781.

Specification of Letters Patent. Patented July 28, 1914.

Application filed July 28, 1911. Serial No. 641,005.

To all whom it may concern:

Be it known that I, LLOYD GROFF COPEMAN, a citizen of the United States of America, residing at Flint, in the county of 5 Genesee and State of Michigan, have invented certain new and useful Improvements in Time-Operating Mechanism for Electric Switches, of which the following is a specification, reference being had therein to the 10 accompanying drawings.

The invention relates to time-controlled mechanism for electric switches, and consists in the peculiar construction of the switch actuating mechanism as hereinafter 15 set forth.

In the drawings.—Figure 1 is a perspective view of a clock to which my improvements are applied; Fig. 2 is a perspective view of the switch actuating arm detached; 20 and Fig. 3 is a rear elevation showing the parts in position for operation.

It is one of the objects of the invention to obtain a construction of time controlled switch operating mechanism which may be 25 applied to an ordinary alarm clock with but slight modification in the construction.

It is a further object to provide means for varying the actuating forks so as to adapt the mechanism to switches of different 30 size.

As shown, A is the ordinary construction of alarm clock provided with a metallic case and having the winding stem B for the time mechanism, the winding stem C for the 35 alarm, the knob D for setting the hands, and the knob E for setting the alarm. To adapt this construction for use in controlling the switch, the case is preferably provided with a spring leg F having a bifurcated foot G 40 for engaging a locking bearing, such as the headed pin H upon the supporting shelf or bracket I. The other legs J of the clock may be of the usual construction, and are adapted to engage with suitable co-acting 45 bearings K by which the clock is fixed in position. Thus, the clock may be readily fixed in position by first engaging the legs J with the bearings K, and then by springing the leg F to engage the bifurcated foot G with 50 the headed pin H.

The switch actuating device comprises an arm L secured to the alarm winding stem C and actuated upon the release of this stem to swing through a partial rotation. The 55 amount of movement is limited by stops M,

preferably in the form of posts projecting outward from the rear face of the case into the path of the arm. N is the handle of the switch, which projects into the path of a roller O secured to the free end of the arm 60 L, the arrangement being such that in the partial rotation of said arm the roll O will strike against the switch handle N and actuate the same to either close or open the switch. 65

For operating switches of different size and under different conditions, the course required will vary. I have therefore made provision for changing the tension of the actuating spring so that it may be adjusted 70 to the requirements. As shown, this is accomplished by a detachable engagement between the arm L and the winding stem, permitting the removal of the arm so that the stem may be wound to place the desired tension 75 on the spring. The arm may then be replaced and secured to the stem and adjusted in position for actuating the switch. If in place of this detachable connection the arm were fixed to the stem the stops M 80 would prevent any turning of the stem more than the angle between the stops.

The specific construction of connection between the arm and the stem, as shown, consists of a slotted bearing P at the inner end 85 of the arm L, which is engageable with a transversely-extending key Q on the stem, while a threaded extension R is anchored with the winding handle S, which latter is provided with a clamping plate T for bearing against the arm L. The arrangement is one which permits of releasing the arm by slightly unscrewing the handle S and withdrawing the slotted bearing P from the key Q, after which the stem may be wound to 95 place the desired tension on the spring. The arm is then replaced and the handle S turned to clamp it in position.

In operation, whenever the alarm is released the arm L will swing through the 100 angle between the stops M, causing the roller O to strike against the switch handle N, opening the switch as desired. At the completion of the operation the roller O is completely withdrawn from the path of the 105 switch handle, which will permit it to be actuated by hand to its initial position.

What I claim as my invention is,—

1. The combination with an alarm clock mechanism, of a winding stem therefor, a 110

switch actuating arm having a slotted bearing for detachably engaging said stem, a transversely extending key on said stem for engaging said slotted bearing, a threaded stud beyond said key, and a winding handle engaging said threaded stud and provided with a clamping face for engaging said arm.

2. The combination with an alarm clock mechanism and a winding stem therefor, of 10 a switch actuating arm having a detachable sliding engagement with said stem, and a

key for winding said stem, said arm being attachable to the stem after the latter has been turned to place the alarm mechanism under the desired tension and said key serving to clamp said arm to said stem. 15

In testimony whereof I affix my signature in presence of two witnesses.

LLOYD GROFF COPEMAN.
